(57) **CLAIM**

The ornamental design for a handling and/or processing station, as shown and described.

DESCRIPTION

FIG. 1 is a front view of a handling and/or processing station.

FIG. 2 is a left-side view of the handling and/or processing station of FIG. 1.

FIG. 3 is a top view of the handling and/or processing station of FIG. 1.

FIG. 4 is a right-side view of the handling and/or processing station of FIG. 1.

FIG. 5 is a rear view of the handling and/or processing station of FIG. 1.

FIG. 6 is a bottom view of the handling and/or processing station of FIG. 1.

FIG. 7 is a front perspective view of the handling and/or processing station of FIG. 1.

FIG. 8 is a front perspective view of a handling and/or processing station that is the same as the handling and/or processing station of FIG. 7 but the handling and/or processing station of FIG. 8 is shown with a door open.

FIG. 9 is a front perspective view of a handling and/or processing station that is the same as the handling and/or processing station of FIG. 7 but the handling and/or processing station of FIG. 9 is shown with a door open and includes a conveyor positioned adjacent the door opening.

FIG. 10 is a front perspective view of a handling and/or processing station that is the same as the handling and/or processing station of FIG. 9 but the handling and/or processing station of FIG. 10 includes a component exiting the door opening and onto the conveyor.

FIG. 11 is a front perspective view of a handling and/or processing station that is the same as the handling and/or processing station of FIG. 7 but the handling and/or processing station of FIG. 11 is shown with a door open and includes a conveyor positioned adjacent the door opening.

FIG. 12 is a front perspective view of a handling and/or processing station that is the same as the handling and/or processing station of FIG. 1 but the handling and/or processing station of FIG. 12 includes a conveyor positioned adjacent the door.

FIG. 13 is a front view of a handling and/or processing station that is the same as the handling and/or processing station of FIG. 1 but the handling and/or processing station of FIG. 13 includes a conveyor positioned adjacent the door.

FIG. 14 is a front perspective view of the handling and/or processing station of FIG. 13.

(Continued)

FIG. 15 is a rear view of the handling and/or processing station of FIG. 5.

FIG. 16 is a front perspective view of the handling and/or processing station of FIG. 15 that is the same as the handling and/or processing station of FIG. 1 but the handling and/or processing station of FIG. 16 includes a conveyor positioned adjacent a door and includes a control panel positioned adjacent a side of the handling and/or processing station.

FIG. 17 is a second front perspective view of the handling and/or processing station of FIG. 15.

FIG. 18 is a front view of the handling and/or processing station of FIG. 15.

FIG. 19 is a front perspective view of a handling and/or processing station that is the same as the handling and/or processing station of FIG. 1 but the handling and/or processing station of FIG. 19 includes a conveyor positioned adjacent a door and includes a control panel positioned adjacent a side of the handling and/or processing station.

FIG. 20 is a front view of the handling and/or processing station of FIG. 19.

FIG. 21 is a front perspective view of a handling and/or processing station that is the same as the handling and/or processing station of FIG. 1 but the handling and/or processing station of FIG. 21 includes a conveyor positioned adjacent a door and includes a control panel positioned adjacent a side of the handling and/or processing station; and,

FIG. 22 is a front perspective view of the handling and/or processing station of FIG. 1.

The broken lines in the drawings depict unclaimed environmental subject matter. Thus, the features shown in broken lines do not form part of the claimed design.

1 Claim, 22 Drawing Sheets
